CLAIM

The ornamental design for a storage unit radio, as shown and described.

DESCRIPTION

FIG. 1 is a top, left and front perspective view of the first embodiment of a storage unit radio, showing our new design;

FIG. 2 is a bottom, right and rear perspective view of the claimed design of FIG. 1;

FIG. 3 is a top view of the claimed design of FIG. 1;

FIG. 4 is a bottom view of the claimed design of FIG. 1;

FIG. 5 is a left-side view of the claimed design of FIG. 1;

FIG. 6 is a right-side view of the claimed design of FIG. 1;

FIG. 7 is a front view of the claimed design of FIG. 1;

FIG. 8 is a rear view of the claimed design of FIG. 1;

FIG. 9 is a top, left and front perspective view of the second embodiment of a storage unit radio, showing our new design;

FIG. 10 is a bottom, right and rear perspective view of the claimed design of FIG. 9;

FIG. 11 is a top view of the claimed design of FIG. 9;

FIG. 12 is a bottom view of the claimed design of FIG. 9;

FIG. 13 is a left-side view of the claimed design of FIG. 9;

FIG. 14 is a right-side view of the claimed design of FIG. 9;

FIG. 15 is a front view of the claimed design of FIG. 9; and,

FIG. 16 is a rear view of the claimed design of FIG. 9.

(Continued)

The broken lines are included for the purpose of illustrating portions of the storage unit radio and form no part of the claimed design.

1 Claim, 16 Drawing Sheets
